US00D437880S

(12) **United States Design Patent**
Chiba et al.

(10) Patent No.: **US D437,880 S**
(45) Date of Patent: **** Feb. 20, 2001**

(54) **SET OF CONTROL BUTTONS AND INDICATOR LIGHT FOR COMPUTER PRINTER**

(75) Inventors: **Toshimi Chiba; Tetsuya Sekine**, both of Yokohama; **Hitomi Ito**, Tokyo; **Manabu Inoue**, Ootsu, all of (JP)

(73) Assignee: **Canon Kabushiki Kaisha**, Tokyo (JP)

(**) Term: **14 Years**

(21) Appl. No.: **29/111,970**

(22) Filed: **Oct. 8, 1999**

(30) **Foreign Application Priority Data**

Apr. 12, 1999 (JP) 11-9489

(51) LOC (7) Cl. **18-02**

(52) U.S. Cl. **D18/56**; D18/50

(58) Field of Search D18/56, 50, 54-55; 400/613, 613.1-613.4, 691-694, 690.1-690.4

FIG. 3

UNITED STATES PATENT AND TRADEMARK OFFICE
CERTIFICATE OF CORRECTION

PATENT NO. : Des. 437,880 S
DATED : February 20, 2001
INVENTOR(S) : Toshimi Chiba et al.

Page 1 of 4

It is certified that error appears in the above-identified patent and that said Letters Patent is hereby corrected as shown below:

The title page should be deleted to appear as per attached title page.

The sheet of drawing consisting of figures 2 and 3 should be deleted to appear as per attached figures.

Signed and Sealed this

Thirteenth Day of September, 2005

A handwritten signature in black ink, appearing to read "Jon W. Dudas", is centered within a rectangular dotted box.

JON W. DUDAS
